UNITED STATES PATENT OFFICE.

JAMES STOTT, OF LONDON, ENGLAND.

GAS-REGULATOR.

SPECIFICATION forming part of Letters Patent No. 354,844, dated December 21, 1886.

Application filed August 19, 1886. Serial No. 211,314. (No model.) Patented in England May 28, 1886, No. 7,197.

To all whom it may concern:

Be it known that I, JAMES STOTT, a subject of the Queen of Great Britain, residing at 174 Fleet Street, in the city of London, England, 5 have invented a new and useful Gas-Regulator, (for which I have obtained a patent in Great Britain No. 7,197, bearing date May 28, 1886,) of which the following is a specification.

This invention has for its object to provide a 10 novel gas-regulator for regulating or controlling the flow of gas to the burners of street-lamps, whereby any determined number of feet of gas per hour can be supplied to the burner-tips notwithstanding variations or the amount 15 of pressure in the gas-mains, provided the initial pressure is always above that for which the regulator is adjusted.

The object of my invention I accomplish by the construction and combination of devices 20 hereinafter described and claimed, reference being made to the accompanying drawings, in which—

Figure 1 is a sectional elevation of a gas-regulator embodying my invention; Fig. 2, a 25 detail plan view of the dome-shaped float and regulating-valve disk, and Fig. 3 a sectional elevation showing the position of the parts when the gas is burning at the burner-tip.

In order to enable those skilled in the art to 30 make and use my invention, I will now describe the same in detail, referring to the drawings, where—

The letter A indicates a hollow casing, having its bottom wall centrally raised to provide 35 an annular basin, C, for containing mercury or other sealing liquid, said raised part of the casing constituting an arched shield, C', to prevent the mercury from spilling if the casing be tilted. The shield C' is provided with a de- 40 pending tube, C', which is screwed upon the gas-inlet pipe B, and in the said tube are seated two perforated diaphragms or bridge-pieces, L, through which passes a vertically-movable stem, H, carrying a dome-shaped float, D, the

45 lower edge of which dips in the mercury in the basin C, so that a seal is formed at this point. The stem projects upward through the float and carries a cone-valve, I, at its upper extremity, adapted to seat in the lower open end 50 of a depending tube, J, formed with a detachable cover, K, having a screw-threaded connection with the casing. This cover carries

the burner-tip M, which communicates with the depending tube J.

The top part of the dome-shaped float D is 55 provided with a series of orifices, E, two or more, controlled by a valve-disk, F, having a corresponding number of orifices, G. This valve-disk is concaved on its under side to conform to and rest upon the top surface of the 60 float, and it is provided with a central opening, through which the valve-stem H loosely passes in such manner that the valve-disk is centrally journaled on the valve-stem between the top surface of the float and the base of the cone-valve I. The valve-disk is capable of being rotated on the valve-stem to bring its orifices G into and out of coincidence with the orifices in the float. By turning the valve-disk the orifices E in the float can be more or less closed 65 to determine the quantity of gas that shall 70 pass to the burner-tip.

In the event of the quality of gas being reduced—say from thirty to twenty candle-power—it becomes necessary to pass a larger 75 number of feet of gas to the burner-tip in order to provide the desired illuminating power. This is readily effected by rotating the valve-disk to enlarge the gas passage-ways formed by the orifices E and G. The cone-valve entering the lower end of the depending tube on the cover more or less closes this tube, and thus the gas-pressure in the casing and in the inlet-pipe equilibrates the floats. The valve-stem 80 H, being guided in its vertical motion by the 85 diaphragms or bridge-pieces L, produces a level dip of the float in the mercury or other liquid, and the latter provides a sealed joint, so that the gas can only enter the casing and pass to the burner-tip through the orifices in the float 90 and valve-disk.

I am aware of the gas-regulators disclosed by German Patent No. 19,794 and by United States Patents Nos. 157,280 and 213,335, and I do not wish to be understood as broadly 95 claiming such regulators.

Having thus described my invention, what I claim is—

1. A gas-regulator consisting of the casing A, having a basin, C, for containing mercury 100 or other sealing liquid, and provided with a depending tube for connecting with a gas-inlet pipe, the bridge-pieces L in the said depending tube, the valve-stem H, having a valve, I,

and guided by the bridge-pieces, a dome-shaped float, D, mounted on the valve-stem and dipping in the liquid seal, and provided with a series of orifices, E, a valve-disk, F, centrally journaled and rotatable on the valve-stem, and having orifices G, and a cover, K, having a tube, J, on which the valve of the valve-stem is adapted to seat, substantially as described.

2. A gas-regulator consisting of a casing, A, having a centrally-raised shield, C', forming a basin, C, for mercury or sealing liquid and provided with a depending tube, C², containing the upper and lower bridge-pieces L, the valve-stem H, having a valve, I, and guided by the bridge-pieces, a dome-shaped float, D, mounted on the valve-stem, dipping in the liquid seal, and provided with a series of orifices, E, a valve-disk, F, in contact with the float, centrally journaled and rotatable on the valve- 20 stem, and having orifices G, and a cover, K,

having a tube, J, on which the valve of the valve-stem is adapted to seat, substantially as described.

3. The combination, with the vessel A, having the liquid-basin C, the dome-shaped float 25 D, having a series of orifices, E, the cover K, and the valve-stem H, extending through the top of the float and provided at its upper end with a valve, I, of the concaved valve-disk F in contact with the float, having a series of orifices, G, and centrally journaled and rotatable on the valve-stem between the base of the valve and the top surface of the float, substantially as described.

JAMES STOTT.
